UNITED STATES PATENT OFFICE.

DONALD F. WHITING, OF NEW YORK, N. Y., ASSIGNOR TO WESTERN ELECTRIC COMPANY, INCORPORATED, OF NEW YORK, N. Y., A CORPORATION OF NEW YORK.

ELECTRIC-CURRENT TRANSMISSION.

Application filed May 28, 1923. Serial No. 641,840.

This invention relates to transmitting electric currents, especially to repeating telephone currents, and aims to accomplish such repeating efficiently and without undue dis-
5 tortion.

In accordance with the invention the transmission characteristics of an electron tube repeater or the like are controlled preferably by providing inductance effectively in series 10 in the input circuit of the repeater and so arranging a condenser in the repeater input circuit as to provide capacity effectively across the input circuit, the inductance tending to resonate with the tube capacity and 15 the capacity between the winding turns of the transformer to raise the gain frequency curve of the repeater at the higher frequencies to be transmitted, and the capacity of the condenser cooperating with the inductance to 20 give the desired shape of this part of the curve. For instance, in case the adjustment of the inductance to raise this part of the curve to the desired degree for one gain setting of the repeater tends to cause an unduly 25 large rise for another gain setting of the repeater, the condenser may be used to prevent such undue rise.

The different gain settings of the repeater may be obtained by employing between the 30 incoming line and the input terminals of the amplifier a device having a variable ratio of input voltage to output voltage, as for example, an input transformer having taps on its secondary winding; and the condenser 35 may be so arranged as to provide capacity connected effectively across the secondary winding of the transformer by adjustment of the transformer from one gain setting to another, as for instance from a higher to a 40 lower gain setting. This action of the condenser may serve to compensate for variations in the effect of the tube capacity upon the repeater gain as the gain setting is changed, whether inductance is inserted 45 effectively in series in the input circuit of the repeater to resonate with the tube capacity or not.

Fig. 1 of the accompanying drawings is a 50 circuit diagram of one embodiment of the invention; Figs. 2 and 3 are curves for facilitating explanation of the invention; Figs. 4, 5, 6 and 7 are circuit diagrams illustrating modifications of the form of the invention shown in Fig. 1; and Fig. 8 is an elevation 55 of one type of structure which may embody

the transformer and compensating condenser of Fig. 1, 4, 5 or 6.

In Fig. 1, currents such for example as speech frequency currents are repeated from a line 11 to a line 12 by means of an electron tube amplifier 13. The line 11 is preferably terminated by a resistance 14 of approximately the impedance of line 11 (after the fashion disclosed in K. S. Johnson Patent No. 1,432,863, October 24, 1922) and across this resistance is connected the primary winding 15 of an amplifier input transformer 16, an inductance 17 and a condenser 18 preferably being connected in series with the winding 15, for reasons appearing hereinafter. If the leakage inductance of the transformer is made sufficiently great to give an effective leakage inductance of approximately the value of inductance 17, this leakage inductance may serve the purpose of the 75 inductance 17. The secondary winding 19 of the input transformer has tap conductors 1 to 9, the tap conductor 1 being connected to the cathode of the tube 13, the control electrode or grid of which may be connected to 80 any of the tap conductors by means of an adjustable contact 20 at the end of a conductor 21 leading from the grid (all after the fashion disclosed and claimed in R. C. Mathes Patent No. 1,495,422, issued May 27, 1924). A condenser 25 is preferably connected between the tap conductor 9 and the grid, for reasons appearing hereinafter, and an output transformer 31 is preferably interposed between the tube 13 and the line 12. 90

The curves of Fig. 2 are observed gain frequency curves, of the repeater for different settings of the contact 20, all of these curves having been taken with the inductance 17 and condenser 25 out of circuit, and all of these curves except the curve 9 for tap 9 having been taken with the condenser 18 in circuit. Curves 2, 3, 4, 5, 6, 7, 8 and 9 correspond to the taps of the same numbers, respectively. The ordinates of the curves give the gain in terms of miles of standard cable.

The curves of Fig. 3 are corresponding 105 observed gain frequency curves of the repeater with the inductance 17 and the condensers 18 and 25 in circuit, the capacity of the condenser 25 having been maintained at a constant value of 120 mmf. The inductance 17 was 13 milhenries, the capacity 18 was 3.5 mf., and the tube 13 was a type 101-B 110

Western Electric vacuum tube. The impedances of line 11, resistance 14 and line 12 were 900 ohms, 900 ohms and 700 ohms respectively, the impedance ratio of the step 5 up transformer 16 was 900:600,000 for the highest gain setting and the ratio of transformer 31 was 6,000:700. Curves 2', 3', 4', 5', 6', 7', 8' and 9' correspond to taps 2, 3, 4, 5, 6, 7, 8 and 9 respectively.

10 Considering now the action of the repeater of Fig. 1 in its highest gain setting but with the inductance 17 and the capacities 18 and 25 out of circuit, the effective input impedance of the tube 13 is high relative to the 15 impedance of the secondary winding of transformer 16 at low frequencies, but at the higher frequencies of the voice range the capacity between the tube electrodes and the capacity within the coil itself have an appreciable effect. For these reasons the transformer presents an inductive reactance to the line in the lower part of the voice range of frequencies and a capacitive reactance in the upper part of the voice frequency range. If 20 no compensation for the effects of these reactances is provided, the repeater may give a desired gain in the middle portion of this frequency range and yet the transmission may fall off considerably at the upper and 25 lower parts of the range as instanced in the curve 9^a of Fig. 2, with resulting distortion of the speech signals. This would also result in poor transmission of ringing currents which in practice usually have a low frequency, as for example, 135 cycles per second. Therefore, as disclosed in the patents 30 of W. L. Casper, Nos. 1,530,648 and 1,530,649 issued March 24, 1925, there is provided in series with the primary winding 15 the inductance 17 having such a value that this 35 inductance (and the leakage inductance of the transformer where the leakage inductance is of a material value) will resonate with the capacitive reactance described above at a frequency in the neighborhood of the upper 40 part of the voice frequency range and thereby, as indicated by curve 9' of Fig. 3, prevent the transmission from materially falling off at the higher speech frequencies and 45 further, as disclosed in the patent of P. H. Pierce, No. 1,530,613, issued March 24, 1925, the condenser 18 is provided to annul the inductive reactance of the transformer at frequencies in the lower part of the voice range, 50 the action of this condenser being to increase the gain of the repeater at the lower frequencies of the voice range, as indicated by a comparison of the curves 9 and 9^a of Fig. 2, so that the gain frequency characteristic 55 of the repeater will not fall off unduly at these low frequencies (although at still lower frequencies the gain will of course be diminished, instead of increased, by the condenser 18).

60 Considering now the effect of changing the

gain setting of the repeater of Fig. 1 when the inductance 17 and the capacity 25 are not in circuit, it appears that as the contact 20 is moved from tap 9 to lower voltage taps the effect of the input capacity of the tube 70 13 in causing the gain at the higher frequencies of the speech frequency range to be lowered less than the gain at lower frequencies is reduced as indicated by comparison of curves 9, 8 and 7, and that after this movement of contact 20 has progressed past tap 7 the gain at the higher frequencies of the voice range becomes greater than the gain at lower frequencies, as instanced in curves 6, 5, 4, 3 and 2, this latter effect being 75 due apparently to the approach toward the higher speech frequencies of the frequency of resonance of the leakage inductance of the transformer with the input capacity of the tube and the capacity between the winding turns of the transformer. Thus, while speech transmission may be practically distortionless when the contact 20 is on tap 7, the repeater may distort considerably at other gain settings. 80

85 As noted above, the distortion for the highest gain setting may be overcome by inserting inductance 17 in circuit, as indicated by curve 9' of Fig. 2, the resonance condition which makes curve 9' horizontal practically 90 throughout the length of the curve being analogous to that which makes curve 7 horizontal throughout its length. However, after the insertion of inductance 17 the distortion for low gain settings will probably 95 100 be even worse than before, the excess of the gain at high frequencies over the gain at low frequencies being increased. To reduce the distortion for low gain settings, the condenser 25 is connected in circuit. If the 105 capacity of condenser 25 remains constant, as the contact 20 is moved from high voltage to low voltage taps the apparent capacitive reactance of this condenser as seen from the primary winding 110 of the transformer varies inversely as the square of the ratio of the number of secondary turns across which the condenser is connected to the number of turns in the primary winding of the transformer; and this 115 variation of apparent capacitive reactance tends to compensate for the variation of the apparent input capacitive reactance of the tube as seen from the primary winding of the transformer, this latter apparent capacitive reactance varying inversely as the square of the ratio of the number of secondary turns across which it is connected to the number of primary turns of the transformer. If the capacity of condenser 25 is not to be 120 125 varied, this condenser should have a capacity somewhat greater than the input capacity of the tube 13, rather than equal to the input capacity of the tube as might be expected on first thought; for if the two capacities are 130

equal, then when the contact 20 engages the middle of the secondary winding of the transformer there will be substantially no current through the conductor 21 (the drop across condenser 25 being practically equal to that across the input capacity of the tube since the negative grid potential from battery C insures that the resistance of the tube is of the order of infinity), and the two capacities will in effect be in series across the secondary winding, so that their combined reactance presented to the secondary winding will be twice the reactance which the input capacity of the tube presents to the secondary winding in the highest gain setting of the repeater.

However, the capacity of condenser 25 may be varied as the setting of contact 20 is changed, where it is desired to reduce distortion to a minimum for the various gain settings. Moreover, a close approach to distortionless transmission for the various gain settings may be obtained with automatic variation of the capacity of the compensating condenser in response to movement of the gain setting contact, one means for accomplishing this being indicated in Fig. 4 wherein the parts are the same as in Fig. 1 except that a contact 20^a and a condenser 25^a connected by a shaft 35 have replaced the contact 20 and condenser 25. The condenser 25^a comprises a fixed semi-circular plate 36 connected to the grid of the tube by a conductor 37, and also comprises a plate 38 attached to and movable with the shaft 35 which moves contact 20^a over the tap conductors 1 to 9. The condenser 25^a may have its plates so shaped, or may be otherwise so designed, as to have the requisite amount of capacity to perform its compensating function with a high degree of accuracy in each operative position of contact 20^a. As shown in Fig. 4, the voltage between any two adjacent taps may be the same, and the outline of plate 38 is an approximately Archimedean spiral, so that as contact 20^a is moved counterclockwise from the position shown the rate of decrease of the capacity of condenser 25^a with the angular displacement of contact 20^a increases from a minimum, slowly for some time but always more and more rapidly until the contact 20^a and the plate 38 have moved through 180°. When the contact 20^a is moved from tap 9 to tap 5 the apparent impedance of the input capacity of the tube as seen from the primary winding of the transformer increases in the ratio of 1 to 4, and in order to compensate for this increase the apparent impedance of the condenser 25^a as seen from the primary winding of the transformer when the contact 20^a is on tap 5 should be approximately four thirds of the apparent impedance that the input capacity of the tube would have were it seen from the primary winding of the

transformer with the contact 20^a on tap 9. That is, when contact 20^a is on tap 5, the impedance of condenser 25^a should be equal to one third of the impedance of the input capacity of the tube, which means that the capacity of the condenser should then be equal to three times the input capacity of the tube. As the contact 20^a approaches very close to the zero gain setting, the value of the capacity of condenser 25^a should of course closely approach the value of the input capacity of the tube, since the apparent input capacity of the tube as seen from the primary winding of the transformer is negligibly small for such a setting of contact 20^a.

Instead of connecting an automatically varied compensating condenser between tap 9 and the grid of the tube, an automatically varied compensating condenser may be connected across the grid and filament of the tube as shown at 25^b in Fig. 5, which is otherwise like Fig. 4 except that the condenser 25^b is somewhat different from condenser 25^a. The condenser 25^b comprises a fixed plate 40 connected to the grid of the tube 13 by a conductor 41, and also comprises a plate 42 connected to the filament by conductor 43 and rotatable with shaft 35 which engages a gain adjusting contact 20^b with the tap conductors 2 to 9. The outline of plate 42 is approximately an Archimedean spiral, and as contact 20^b is moved counterclockwise through 180°, from the position shown, the capacity of condenser 25^b increases from zero to a maximum, the rate of increase with angular displacement, being relatively slow at first and increasing throughout the 180° displacement. When the contact 20^b is on tap 5 the capacity of condenser 25^b should be approximately three times the input capacity of the tube, as explained for the circuit of Fig. 4; but when the contact 20^b is in the lower gain settings the capacity of condenser 25^b should be large, and the capacity necessary will depend upon how low a voltage it is desired to tap from the transformer, or in other words how low a gain it is desired to obtain at the lowest gain setting of the repeater.

The requisite capacity of the compensating condenser may be reduced by employing a condenser arrangement such as is shown in Fig. 6, which is otherwise like Figs. 4 and 5. In Fig. 6 a compensating condenser 25^c comprises a fixed plate 45 connected to the filament of tube 13, and also comprises a plate 46 connected to tap 9 by a conductor 47, the plate 46 being rotatable by the shaft 35 which engages a gain adjusting contact 20^c with taps 2 to 9. The outline of plate 46 is approximately an Archimedean spiral, and as contact 20^c is rotated counter-clockwise through 180°, from the position shown, the capacity of condenser 25^c increases from zero to a maximum, the rate of increase

with angular displacement being relatively great at first and decreasing throughout the 180° displacement.

Fig. 7 is like Fig. 5 except that instead of 5 the condenser 25^b of Fig. 5, a separate condenser unit 25^d is employed for each position of a gain adjusting contact 20^d, which corresponds to the gain adjusting contact 20^b of Fig. 5, the contact 20^d connecting 10 one pole of the appropriate condenser unit to whichever one of the taps 2 to 9 happens to be in engagement with the contact. The condensers 25^d have different values, the requisite value of the particular one of these 15 condensers which is in use for any given gain setting of the repeater being the same as the requisite value of the condenser 25^b of Fig. 5 for the same gain setting.

In circuits such as those of Figs. 1 and 4 20 to 7, it is desirable to avoid the introduction of excessive capacities due to leads and switching means, and Fig. 8 shows a structure which attains this end. The transformer 16 and a housing 51 therefor are 25 mounted on a base 50. The housing carries a condenser 25^e which comprises upper and lower nonconducting plates 55 and 56, respectively, connected by upright members 57. On the plate 55 are mounted fixed contacts such as contacts 1 to 9, only one of 30 these contacts, 5 being shown. Short tap conductors from the transformer 16 lead to these contacts such as 5, one of these tap conductors being indicated at 58. A contact 20^e may be rotated by a shaft 35' to engage the various contacts such as 5, the shaft having bearings in the plates 55 and 56. Fixed condenser plates 60 of conducting material are mounted on the members 40 57, and condenser plates 61 of conducting material are mounted on shaft 35' to rotate therewith, the plates 60 and 61 being so shaped or related that the rotation of shaft 35' varies the capacity of the condenser 25^e 45 in the desired manner, as for instance in the manner in which the capacity of the condenser 25^a, 25^b or 25^c is varied by rotation of shaft 35. The transformer and condenser of Fig. 8 may be connected in any circuits for which they are suited. For instance, they may be arranged in circuits of 50 the types shown in Figs. 4 to 6 as the transformer 16 and the condenser 25^a, 25^b or 25^c are arranged in those circuits.

55 The straps interconnecting the several fixed plates 60 and movable plates 61 of condenser 25^e have been omitted in Fig. 8 for the sake of clarity, and the interconnections between fixed and movable plates 60 and 61 60 and the contact brush 20^e and contacts 1 and 9 where they may occur have also been omitted for the same reason and because of the differences in the connections of Figs. 4, 5 and 6.

65 Although the invention has been described

above with special reference to the transmission of currents in the voice frequency range, it is not restricted to transmission of such frequencies, for its principles are applicable also to the transmission of currents of other frequencies. It may be realized in various embodiments differing from the specific forms depicted, without departing from the scope of the appended claims. 70

The invention claimed is:

1. A repeating circuit comprising an electron tube, an input transformer therefor having an inductance effectively in series with a winding of said transformer for resonating with the input capacity of the tube 80 and the capacity between the winding turns of the transformer at a frequency in the neighborhood of a frequency to be repeated, and a condenser providing a capacity effectively across the secondary winding of said 85 transformer of such magnitude as to materially lower the gain of the repeater circuit at the frequency of said resonance.

2. A circuit for repeating currents of a frequency range adequate for speech transmission comprising a space discharge amplifying device having input electrodes, an input transformer for said device having a winding provided with taps for connection to one of said input electrodes whereby different gain settings for said circuit may be obtained, inductance effectively in series with a winding of said transformer and of such value as to decrease the distorting effect of said circuit on the higher frequencies to be transmitted for the higher gain settings of said circuit, and means providing capacity effectively across a winding of said transformer of such value as to decrease the distorting effect of said circuit on the 100 higher frequencies to be transmitted at the lower gain settings of said circuit. 105

3. A circuit for repeating currents of a frequency range adequate for speech transmission, said circuit comprising an electron tube, an input transformer therefor having an inductance effectively in series with a winding of said transformer for resonating with the input capacity of the tube and the capacity between the winding turns of the transformer at a frequency in the neighborhood of the upper frequencies of the voice range, and a condenser providing a capacity effectively across the secondary winding of said transformer for controlling the gain of said circuit at frequencies at least as high as a frequency in the neighborhood of the upper frequencies of the voice range. 110

4. A repeater for currents of a frequency 125 range adequate for speech transmission, said repeater comprising an electron tube having input electrodes, an input transformer for said tube having a winding provided with taps for connection to one of said electrodes, 130

- so that its variation in capacity for a given 50
change in said gain setting is proportioned.
to compensate for the variation in the apparent
input capacitive reactance of said tube
with the change in gain setting tending to
cause distortion in said circuit. 55
5. A circuit comprising an electron tube
having an electrode, an input transformer
therefor having a winding provided with
taps, means for adjustably connecting said
electrode to said taps, a variable condenser
between said electrode and a fixed one of
said taps, and means operable by said first
mentioned means in moving from higher to
lower voltage taps, for decreasing the capacity
of said condenser at a diminishing rate 60
as said first mentioned means changes the
connection of said electrode to said taps in
such manner as to decrease the potential of
said electrode at a constant rate. 65
6. A circuit comprising an electron tube
having an electrode, an input transformer
therefor having a winding provided with
taps, means for adjustably connecting said
electrode to said taps, and a condenser be- 70
tween said electrode and a fixed one of said
taps, said condenser having a capacity of
such value as to compensate for variations
of the effective capacity provided by the
input capacity of said tube across said wind- 75
ing, as the connection of said electrode to
said taps is varied. 80
7. A circuit comprising an electron tube
having two input electrodes, an input trans- 85
former for said tube, said transformer hav-
ing a winding provided with taps, means
connecting one of said electrodes to one end
of said winding, a condenser connected be- 90
tween the other of said electrodes and the
other end of said winding, and means for
adjustably connecting said other electrode
to said taps to vary the gain setting of said
circuit, and for simultaneously varying the 95
capacity of said condenser, said condenser
being designed with respect to said means.

In witness whereof, I hereunto subscribe
my name this 25th day of May, A. D., 1923.

DONALD F. WHITING.
